(57) **CLAIM**

The ornamental design for a wearable blanket, as shown and described.

DESCRIPTION

FIG. 1 is a top right front perspective view of a wearable blanket in accordance with the present invention;

FIG. 2 is a top left back perspective view thereof;

FIG. 3 is a front side view thereof;

FIG. 4 is a backside view thereof;

FIG. 5 is a right side view thereof;

FIG. 6 is a left side view thereof;

FIG. 7 is a top side view thereof;

FIG. 8 is a bottom side view thereof;

FIG. 9 is a perspective view thereof worn by a person standing; and,

FIG. 10 is a perspective view thereof worn by a person seated.

The broken lines within the wearable blanket represent stitching and form part of the claimed design. The broken lines in FIGS. 9 and 10 represent environment and form no part of the claimed design.

1 Claim, 10 Drawing Sheets
